United States Patent Office.

JOHN ROBBINS ROSE AND EDWARD CALEY, OF PHILADELPHIA, PENNSYLVANIA,
ASSIGNORS TO SAMUEL BUDD SEXTON, OF BALTIMORE, MARYLAND.

Design No. 4,063, dated May 24, 1870.

DESIGN FOR SCREEN FOR FIRE-PLACES.

The Schedule referred to in these Letters Patent and making part of the same.

We, JOHN ROBBINS ROSE and EDWARD CALEY, of Philadelphia, county of Philadelphia, State of Pennsylvania, have invented or produced a Design for a Shield or Screen for Fire-Places or Fire-place Stoves, of which the following is a specification.

The design consists in the peculiar configuration and ornamentation of the screen or shield for which Letters Patent were granted to S. B. SEXTON, on the 14th day of December, 1869.

In the accompanying drawings—

A represents the frame of a fire-place or fire-place stove, the latter being covered by the screen B, which forms the subject of my design.

This screen is fitted snugly to the arched opening of the frame A, is simply rounded below, and made of a concavo-coussé form above.

The screen is edged on the arched and side edges with a scalloped molding, and has an upper central shield or panel, D, containing a scroll ornament with open-work. Below this shield are three panels, E E

E, defined by ornamental scrolls, and containing open lattice-work.

At the bottom of the screen is a door, F, ornamented as shown.

The other ornaments of the stove are too clearly illustrated by the drawings to need specific explanation.

Claim.

The design, substantially as described, and as illustrated in the drawings, of a shield or screen for fire-place or fire-place stove.

In testimony whereof we have signed our names to this specification in the presence of two subscribing witnesses.

J. ROBBINS ROSE.
EDWARD CALEY.
